INVENTOR,
RALPH M. HEINTZ.
BY Donald H. Lippincott

ATTORNEY.

UNITED STATES PATENT OFFICE

RALPH M. HEINTZ, OF PALO ALTO, CALIFORNIA, ASSIGNOR TO HEINTZ & KAUFMAN, LTD., OF SAN FRANCISCO, CALIFORNIA, A CORPORATION OF NEVADA

CARBURETOR

Application filed November 24, 1930. Serial No. 497,818.

My invention relates to carburetors for internal combustion engines, and particularly to carburetors for engines where the conditions of use make the application of the usual float chamber impracticable.

Among the objects of my invention are: First, to provide a carburetor adapted to small, high-speed engines of the two-cycle type; second, to provide a carburetor comprising few and simple parts; third, to provide a carburetor which will supply a proper fuel mixture over a wide range of operating speed; fourth, to provide a carburetor offering low frictional resistance to the flow gases; and fifth, to provide a carburetor which will operate from a fuel tank mounted beneath it, and wherein the change of adjustment required with changing fuel level in the tank is, in general, unnecessary, and where such change is required it may be easily accomplished.

Other objects of my invention will be apparent or will be specifically pointed out in the description forming a part of this specification, but I do not limit myself to the embodiment of my invention herein described, as various forms may be adopted within the scope of the claims.

Referring to the drawing:

Figure 1 is a plan view of a carburetor embodying my invention.

Figure 2 is an axial sectional view of the carburetor.

Figure 3 is a transverse sectional view of the carburetor, the plane of section being indicated by the line 3—3 of Figure 2.

Figure 4 is an axial sectional view of the lower portion of the carburetor, the plane of section being perpendicular to that of Figure 1, as indicated by the line 4—4 of Figure 3.

In general terms, the carburetor of my invention comprises a U-shaped Venturi tube having a fuel jet opening into the curved portion of the tube. This fuel jet is preferably connected to a substantially vertical feed pipe, the lower end of which is provided with a foot valve to prevent return flow of fuel. A throttle comprising a diaphragm is mounted across both arms of the U-tube, and is provided with apertures which are preferably

dissimilar in form, so that the intake arm of the tube is less restricted than the outlet arm when the throttle is nearly closed, both arms being unrestricted when the throttle is wide open.

Describing a preferred form of my invention in greater detail, the body of the carburetor comprises two principal parts which are preferably castings. The lower portion of the body comprises a plate 5 which is circular in general form and is provided with a pair of projecting lugs 6 for attaching the upper casting. Depending from the plate are a cylindrical flange or skirt 7, and a semitoroidal U-tube 8. The openings 9 and 10 of the U-tube through the surface of the plate are circular, but its central portion is somewhat flattened, as indicated by the reference character 12, so that it constitutes a venturi. A short cylindrical boss 13 projects upward from the center of the plate, and this boss is drilled and threaded for the stem 15 of a needle valve. Threaded into the bottom of the U-tube immediately beneath the needle valve is a fuel pipe 16, into the top of which is fitted a jet 17 which forms the seat of the valve.

Fastened to the lower end of the fuel pipe is a foot or check valve 18 of familiar type, which prevents the return through the valve of liquid which has once been drawn upward into the pipe.

The throttle comprises a circular diaphragm 20, which is pivotally mounted upon the boss 13. The diaphragm is provided with two apertures 21 and 22. The aperture 21 is approximately egg-shaped in form, while the aperture 22 is circular. These apertures are so arranged that when the diaphragm is rotated so that the aperture 22 coincides with the aperture 10, the arc forming the large end of the egg-shaped aperture 21 also coincides with the edge of the opening 9 and both arms of the U-tube are unrestricted. When the diaphragm is rotated so as to move the apertures 22 and 10 out of alignment, the tapered end of the egg-shaped aperture 21 overlies the aperture 9. This causes the closing of the throttle to restrict the opening 10 of the U-tube more rapidly than the opening 9.

A rim 23 projects slightly above the plane of the plate 5, and partly surrounds the throttle 20, in order to leave space in which the throttle may be moved freely. The rim 5 is cut away on one side to form a rabbet 24 through which an arm 25 for moving the throttle projects.

In order to provide a frictional control of the movement of the throttle, the arm 25 is 10 preferably bent back upon itself to form a leaf spring 26 which bears upon the edge of the plate 5, and holds the throttle in any position to which it may be adjusted. In order to strengthen this spring, and provide a 15 convenient grip, a ball-shaped handle 27 is secured to the end of the arm 25.

The upper portion of the carburetor body also comprises a substantially circular plate 30, provided with lugs or ears 31 by which it 20 is secured to the plate 5 by means of the screws 32.

Rising from the plate is a super-structure, roughly like a figure eight in plan, which forms the two rising arms which continue the 25 U-tube. The intake arm 33 is closed at the top, and is provided on either side with an opening 35 for admitting the intake air to the carburetor. I have found that the use of these 30 opposed openings on the sides of the arm greatly increases the effectiveness of the carbureting action as compared with the use of a single opening, or with a U-tube open at the top. This is apparently due to increased 35 turbulence in the air passing through the carburetor.

The outlet arm 36 is conveniently of about 40 the same length as the inlet arm, and receives a curved tube 37 whose upper end is provided with a flange 38 to connect with the intake port of the engine.

The needle valve 15 passes down through 45 the upper casting between the two arms of the U-tube, and is provided with a handle 40 threaded to its upper end. The threaded portion of the handle is slotted, as indicated by the reference character 41, and the slot forms a clamp which may be tightened by a screw 42 to hold the handle firmly in position on the needle valve. The upper end of the valve 50 stem is provided with a screw slot 43, which permits the preliminary adjustment of the valve. This is done by screwing the valve down firmly into its seat in the jet 17, adjusting the handle 40 to the closed position, 55 and then tightening the clamp screw 42.

The needle valve adjustment is held in the desired position by the friction provided by a spring 45 comprising a wire inserted in the under part of the handle, and looped around the stem of the valve. The friction of this 60 spring against the top of the carburetor body prevents unintended movement of the valve.

As the device is ordinarily used, it is 65 mounted directly above the fuel tank, which may be in the base of the engine which the

carburetor supplies. The suction provided by the engine draws the fuel up into the fuel pipe 16, where it is held by the check valve 18. The arrangements of the dissimilar apertures in the throttle have been found to give 70 the proper mixture of fuel and air for all running conditions, without the use of auxiliary jets or other complications.

Experience has shown that the height of the fuel in the tank, as long as the variation does 75 not exceed approximately 6 inches, makes practically no difference in the operation of the carburetor. However, with certain grades of fuel which demand particularly accurate adjustments, such variation as does 80 occur may readily be compensated by a slight movement of the needle valve. In portable engines, for which the carburetor is particularly designed, the needle valve may be used to cut off the fuel supply entirely when the 85 engine is not in operation.

I claim:

1. A carburetor comprising a U-shaped Venturi tube, a fuel jet entering said tube in the curved portion thereof, and a throttle 90 comprising an apertured diaphragm pivotally mounted between the arms of said Venturi tube and arranged across both arms of said U-tube.

2. A carburetor comprising a U-shaped 95 Venturi tube, a fuel jet entering said tube in the curved portion thereof, and a throttle comprising a diaphragm arranged across both arms of said U-tube and having dissimilar apertures therein to cause unequal 100 restrictions in the two arms of the tube.

3. A carburetor comprising a U-shaped Venturi tube, a fuel jet entering said tube in the curved portion thereof, and a throttle comprising a diaphragm pivotally mounted 105 between the arms of said U-tube and arranged across both of said arms and having dissimilar apertures therein to cause unequal restrictions in the two arms of the tube.

4. A carburetor comprising a U-tube having 110 inlet and outlet arms, a fuel jet entering said tube in the curved portion thereof, and a throttle comprising a movably mounted diaphragm arranged across both arms of said U-tube and having apertures asymmetrically 115 arranged therein to restrict said outlet arm to a greater extent than said inlet arm when nearly closed, and to leave both arms unrestricted when open.

5. A carburetor comprising a U-shaped 120 Venturi tube, a fuel jet entering the constricted portion of said tube, a throttle comprising a diaphragm movably mounted across both arms of said tube, a fuel pipe rising substantially vertically to said jet, and a foot 125 valve mounted on said fuel pipe to prevent the return of fuel therethrough.

6. A carburetor comprising a U-shaped Venturi tube having inlet and outlet arms, the end of said inlet arm being closed and 130

an inlet port being formed in the side of said arm, a throttle comprising an apertured diaphragm pivotally mounted between the arms of said Venturi tube and movably arranged across both of said arms, and a fuel jet entering said tube in the curved portion thereof.

5 In testimony whereof, I have hereunto set my hand.

RALPH M. HEINTZ.
